[57] **CLAIM**

The ornamental design for an inline skate hanger, as shown and described.

DESCRIPTION

FIG. 1 is a front elevational view of the inline skate hanger, showing my new design;

FIG. 2 is a right-side elevational view of thereof, the left-side elevational view being a mirror image of the right-side elevational view;

FIG. 3 is a back elevational view of thereof;

FIG. 4 is a bottom plan view thereof;

FIG. 5 is a top plan view thereof; and,

FIG. 6 is a right-side elevational view of the hanger mounted on a vertical surface and holding an inline skate, the surface and the skate being shown as broken line drawings. For illustrative purposes only and forming no part of the claimed design.
